DESIGN FOR A BRASSIÈRE OR SIMILAR ARTICLE

Louis J. A. Amyot, Quebec, Quebec, Canada

Application December 18, 1939, Serial No. 88,991
In Canada November 18, 1939

Term of patent 7 years

To all whom it may concern:

Be it known that I, Louis J. A. Amyot, a subject of the King of Great Britain and resident of the city of Quebec, in the Province of Quebec and Dominion of Canada, have invented a new, original, and ornamental Design for a Brassière or Similar Article, of which the following is a specification, reference being had to the accompanying drawing, forming part thereof.

In the accompanying drawing:

The single figure is a perspective view of a brassière with the shoulder straps broken away, showing my new design.

The main feature of the design resides in the shape, appearance and arrangement of the breast pocket reinforcing panels. The back of the garment is of conventional configuration.

I claim:

The ornamental design for a brassière or similar article, as shown and described.

LOUIS J. A. AMYOT.
